United States Patent Office

Des. 186,245
Patented Sept. 29, 1959

186,245

BOTTLE

Ernest L. Du Pree, Weston, Conn., assignor to Schenley
Industries, Inc., New York, N.Y., a corporation of Delaware

Application June 11, 1959, Serial No. 56,318

Term of patent 14 years

(Cl. D58—8)

I claim:

The ornamental design for a bottle, as shown.
